UNITED STATES PATENT OFFICE.

JOHN HANSEN, OF BETTENDORF, IOWA, ASSIGNOR OF FOUR TWENTY-FIFTHS TO WILLIAM H. MARTIN, TEN TWENTY-FIFTHS TO T. S. CUNNINGHAM, AND ONE TWENTY-FIFTH TO THOMAS McQUARRIE, ALL OF DAVENPORT, IOWA.

MECHANICAL GOLF INSTRUCTOR AND EXERCISER.

Application filed December 29, 1926. Serial No. 157,751.

My invention has reference to a mechanical golf instructor and exerciser, and relates to certain improvements in a device of that type which is set out in my former application for Letters Patent of the United States filed Oct. 25, 1926, and numbered 143,977. Said former application embodied a track of approximately circular form, serving as a guide for a frictionless traveller to which was attached the end of a golf club or stick used in practice. Associated with the traveller was mechanism for controlling the axial movement of the club in its trip round the track, compelling the same to follow the natural movement of the club in making a stroke. Included therewith was a channel in the face of the track and a roller operating therein, by which the controlling mechanism was actuated.

20 In the present invention the channel is replaced by a track on the face of the rail forming the main track, upon the edges of which travels a pair of rollers connected with the control mechanism, and imparting movement thereto. In other respects the construction and operation of the device is the same as in said former invention, except that the traveller rides on the edges of the track instead of on its faces.

30 The particular construction, arrangement, and operation of the various parts of the invention will be more thoroughly understood from the following specification, reference being had to the accompanying drawings, in which;

Fig. 1 shows a fragment of a track upon which the traveller operates, with the traveller in position thereon.

Fig. 2 is a cross-section on the broken line 40 2-2 of Fig. 1.

The reference number 1 indicates a section of track, the main part of which is understood to be of a suitable shape and size to enable a player to stand in a central position and describe a stroke with a golf stick, the track serving as a guide therefor. On one of the faces of the track 1 is a track 2, extending from one end to the other thereof. Slidable on the track 1 is a frame 3, by means of rollers 4 at the corners thereof, and grooved to conform to the semi-circular formation of the edges of the track. In the upper part of the frame, which runs on the inner side of the track, is a bearing 5, in

which is journaled a shaft 6, on the upper end of which is a yoke 7, connected by a swivel pin 8 with the yoke 9 on the end of a stick 10. This stick is shown broken away, and would be of suitable length and shape for use as a golf club.

Projected from the bearing 5 is a bracket 11, supporting a bearing 12, in which is journaled the outer end of a shaft 13, the other end of said shaft being supported in a part of the frame 3. Rotatable on the shaft 13 is a sleeve 14, to which is fixed a bevel-gear wheel 14^a, in engagement with a bevel-gear wheel 15 on the lower end of the shaft 6. A gear-wheel 16 is also fixed to the sleeve 14, and pivoted on the frame 3 as at *a* is an arm 17, on one end of which is a segment gear 17, the teeth of which are in mesh with the teeth of the wheel 16. In the other end of the arm 17 is a pin 19, on which is pivoted a link 20 in the opposite ends of which are rollers 21 and 22, which bear against opposite edges of the track 2.

During a large part of its course the track 2 is in parallel relation with the track 1, near one edge or other of said main track, but in another part it crosses from one side to the other, as indicated in Fig. 1. This results in a rocking movement of the arm 17 and segment gear 18, imparting rotation to the shaft 13, which is communicated through the gearing 14^a and 15 to the shaft 6 and stick 10 connected therewith. This movement is sufficient to give to the stick a half rotation, and the arrangement of the track 2 is such that the movement begins at the right hand side of the player and ends at the opposite side. In the case of the use of an actual golf club this would have the effect of turning the shaft from a position with the face of the club to the front to a position with the face of the club to the rear, following the natural course thereof. It will be observed that the hands of the player will be compelled to follow the movement of the stick, as set forth in said former application, and incorrect playing will soon be corrected.

By having the rollers 21 and 22 supported on a pivoted support there is no possibility of their binding against the sides of the track 2, as would be the case if the link 20 were rigidly connected with the arm 17. The pivot preferably consists of a bolt, on the threaded end of which is a thumb-screw

23, by the release of which the link and rollers can be removed. This will permit free movement of the stick 10, in case it is desired to use the same without hindrance by the gearing and cam track.

In the present invention the efficiency of operation is increased and the operating parts greatly simplified. There is also a considerable advantage in constructing the track with a cam track on its face, and operating the rollers of the travelling frame on the edges of the main track, instead of providing said track with numerous channels, as in said former construction.

15 What I claim, and desire to secure by Letters Patent, is:

1. In a device of the class described, a suitable track provided with a cam-track on one of its faces, a frame provided with 20 rollers operable on said first-named track, an arm carried by said frame and provided with a follower for said cam-track, a pivotal stick connection in said frame, and means for imparting the movement of said arm to 25 said pivotal connection, to suitably rotate the same.

2. In a device of the class described, a suitable track provided with a cam-track on one of its faces, a frame provided with 30 rollers operable on the edges of said first-named track, and provided with a pivotal connection, an arm rockingly mounted on said frame, gearing connecting said arm with said pivotal connection, a link pivoted 35 to the free end of said arm, and rollers on the ends of said link bearing against opposite sides of said cam-track.

3. In a device of the class described, a suitable track and cam-track on one of the faces thereof, a frame movable on said first-named track and pivotal connection mounted thereon, an arm rockingly mounted on said frame, means for imparting the rocking movement of said arm to said pivotal connection, to rotate the same, and a follower for said cam-track detachably connected with said arm.

4. In a device of the class described, a suitable track and cam-track thereon, a frame slidable on said first-named track, a pivot mounted in said frame and stick-coupling connected therewith, an arm rockingly mounted in said frame, gearing connecting said arm with said pivot, a link pivoted to said arm and detachable therefrom, and rollers carried by the ends of said link, engaging the sides of said cam-track.

5. In a device of the class described, a suitable track and cam-track on the face thereof, a frame slidable on said track, a pivot supported in said frame and coupling on the inner end thereof, a bevel-gear wheel on the outer end of said pivot, a bevel gear wheel rotatably mounted and in mesh with said first-named bevel-gear wheel, a gear pinion rotatable with said second-named bevel-gear wheel, an arm pivoted in said frame, and provided on one of its ends with a segment gear in mesh with said gear pinion, and a follower for said cam-track on the other end of said arm.

In testimony whereof I affix my signature.

JOHN HANSEN.
